UNITED STATES PATENT OFFICE

165,900

COMBINED HOLDER AND PERFUME BOTTLES

Helen Sherwood Blauvelt, Montclair, N. J.

Application October 24, 1951, Serial No. 17,095

Term of patent 3½ years

(Cl. D58—26)

To all whom it may concern:

Be it known that Helen Sherwood Blauvelt, a citizen of the United States of America, residing at 89 Gordonhurst Avenue, Montclair, in the county of Essex and State of New Jersey, has invented a new, original, and ornamental Design for Combined Holder and Perfume Bottles, of which the following is a specification, reference being had to the accompanying drawing, forming part thereof.

I claim:

The ornamental design for a combined holder and perfume bottles, shown.

HELEN SHERWOOD BLAUVELT.
